1 Drawing Sheet

1

Genus and species: *Calibrachoa sp.*
Variety denomination: 'KLECA23987'.

BACKGROUND OF THE NEW PLANT

The present invention comprises a new and distinct variety of *Calibrachoa*, botanically known as *Calibrachoa sp.*, and hereinafter referred to by the variety name 'KLECA23987'. 'KLECA23987' originated from a controlled-cross between the female *Calibrachoa* variety 'KLECA20803' (U.S. Plant Pat. No. 33,988) and the male *Calibrachoa* variety 'KLECA22825' (unpatented).

In August 2019, two *Calibrachoa* parental lines, the female variety 'KLECA20803' and the male variety 'KLECA22825', were crossed via a controlled-cross in Stuttgart, Germany and seeds were obtained. The seeds were sown and plants were grown for evaluation. A plant line was selected in May 2020 and subsequently named 'KLECA23987'. In May 2020, 'KLECA23987' was first vegetatively propagated by cuttings. 'KLECA23987' was found to reproduce true to type in successive generations of asexual propagation via cuttings.

SUMMARY

The following are the most outstanding and distinguishing characteristics of this new variety when grown under normal horticultural practices in Stuttgart, Germany.

1. Yellow flower with red veins and a red magenta border; and
2. Mounding plant habit.

DESCRIPTION OF THE PHOTOGRAPH

This new *Calibrachoa* plant is illustrated by the accompanying photograph which shows a close-up of the whole plant.

The photograph is of a 12-week-old-plant grown in a greenhouse in Stuttgart, Germany in June 2022.

2

The colors shown are as true as can be reasonably obtained by conventional photographic procedures.

DESCRIPTION OF THE NEW VARIETY

The following detailed descriptions set forth the distinctive characteristics of 'KLECA23987'. The data which define these characteristics were collected from asexual reproductions carried out in Latina, Italy. Data was collected on 13-week old plants after transplant in Latina, Italy.
